UNITED STATES PATENT OFFICE.

JOHN F. O'CONNOR, OF CHICAGO, ILLINOIS, ASSIGNOR, BY MESNE ASSIGNMENTS, TO
WILLIAM H. MINER, OF CHICAGO, ILLINOIS.

DRAFT-RIGGING FOR RAILWAY-CARS.

977,827.

Specification of Letters Patent.

Patented Dec. 6, 1910.

Application filed May 20, 1908. Serial No. 433,814.

To all whom it may concern:

Be it known that I, JOHN F. O'CONNOR, a citizen of the United States, residing in Chicago, in the county of Cook and State of Illinois, have invented a new and useful Improvement in Draft-Rigging for Railway-Cars, of which the following is a specification.

My invention relates to improvements in draft rigging for railway cars, and more particularly to the construction of the side plates or stop castings which are secured to the draft sills or other frame members of the car, and against which the followers abut.

Draft rigging side plates or stop castings are ordinarily made of malleable iron, and on account of the great length and considerable size of the castings and their somewhat irregular shape, due to the necessity of furnishing them with inwardly projecting shoulders for the followers to abut against on one face, great difficulty is experienced in practically producing them free from casting strains or other weaknesses, which cause them to inadequately withstand the enormous strains, shocks and blows to which they are subjected in practical operation from the draw-bar of the car coupler.

The object of my invention is to provide an improved construction of draft rigging side plate or stop casting, by means of which the difficulties or weaknesses heretofore experienced may be practically overcome.

My invention consists in the novel construction of draft rigging side plate or stop casting herein shown and described and more particularly specified in the claim.

In the accompanying drawing forming a part of this specification, Figure 1 is a plan view partly in horizontal section of a draft rigging having a side plate or stop casting embodying my invention. Fig. 2 is a side elevation of a side plate or stop casting of my invention, showing the inside face of the same. Fig. 3 is an elevation showing the rear face of the same which fits against the side sill or draft timber or member of the car frame. Figs. 4 to 8 are cross sections on lines 4-4, 5-5, 6-6, 7-7 and 8-8 respectively of Fig. 3 and Fig. 9 is a longitudinal section on line 9-9 of Fig. 2.

In said drawing, A represents the center sills, draft timbers or frame members of a car to which the side plates or stop castings

are secured, B the draw-bar, B¹ the draw-bar yoke, C tandem arranged springs, D the side plates or stop castings and E the followers.

Each of the side plates or stop castings D consists of a main web 1, having a substantially right angle inwardly projecting longitudinal flange 2 at its upper edge, and right angle end flanges 3, 3 at its ends, and provided with transverse bends or convolutions 4, 4 near its front and rear ends to form the front and rear stops or shoulders 5, 5, and also provided with a transverse intermediate bend 6 at its middle to form the two middle stops or shoulders 7, 7 for the two intermediate followers to abut against, and provided also with inwardly projecting rectangular bosses 8, 8 to form the supplemental stops or shoulders 9, 9 which limit the movement of the followers and the compression of the springs, said rectangular bosses 8, 8, having also longitudinally extending shoulders or bends 10, 10. This construction leaves the side plates or stop castings D with flat smooth wearing faces 11, 11 for the ends of the followers to engage, surrounding the raised bosses 8, 8, and between the front and rear stops 4, 4 and the middle or intermediate stops 7, 7. And to distribute the metal of the side plate 80 or stop casting D so as to give the casting as a whole great strength against buckling, and at the same time enable the casting to be practically produced free from casting strains or other weaknesses, I provide it 90 on its back face with a series of longitudinally extending end recesses 12, 12, having rounded ends 13 and intervening and marginal longitudinally extending ribs 14, 14, and a series of longitudinally extending intermediate recesses 15, 15 having rounded ends 16 and intervening and marginal ribs 17. The two upper longitudinally extending end recesses 12 have transversely elongated deepened portions 18, the deepened 95 portions 18 being separated by the narrowed portion 19 of one of the ribs 14. The lower recess 12 at each end has no deepened enlargement 18 communicating therewith. The two upper longitudinally extending recesses or depressions 15 have deepened portions 20, 20, separated by the narrowed portion 21 of the rib 17. The transversely extending cavities or recesses 22 in the back 100 face of the side plate or stop casting D 110

formed by the inwardly projecting bosses 8 on the front face of the casting are bridged by central webs 23, furnished with bolt holes 24 to receive the bolts *d* by which the side 5 plate or stop castings D are secured to the center sills, draft timbers or other frame members of the car.

As the recesses or depressions 12, 15 in the back of the side plate or stop casting D 10 extend longitudinally and have rounded ends 13, although the recesses 12, 12, 12, 15, 15, 15 are contiguous to each other, they nevertheless do not produce any continuous transverse shoulder or thickened rib extending 15 across the back of the casting such as would tend to cause transverse weakness or strain in the casting under shrinkage. The rounded ends 13 of the recesses 12, 15 prevent or avoid transverse shoulders which 20 would materially weaken the side plate; as in it, when in service, the strains are chiefly tensile or in the direction of its length.

I claim:—

In a draft rigging, a side plate stop casting 25 having on its inner face front, rear, intermediate and supplemental stops for the

followers to abut against, and consisting of a main web 1, furnished with transverse bends or convolutions 4, 4, 6, to form said stops, and inwardly projecting rectangular bosses 8, 8 to form the supplemental stops, and having a smooth flat bearing face 11 between the stop shoulders for the ends of the followers to wear against, said stop casting having on its back or rear face a series of longitudinally extending end recesses or depressions with ribs between the same and a series of longitudinally extending intermediate recesses with longitudinal ribs between same, said longitudinally extending recesses or depressions on the back face of said stop casting having rounded ends, the upper longitudinally extending end and intermediate recesses or depressions on the back face of the casting having deepened portions 18, 18 and 20 formed by said bends or convolutions 4, 4 and 6, substantially as specified.

JOHN F. O'CONNOR.
